SIGNAL-BOX.

1,079,309.

Specification of Letters Patent.

Patented Nov. 18, 1913.

Application filed May 25, 1911. Serial No. 629,415.

To all whom it may concern:

Be it known that we, CLARENCE E. BEACH and HERMAN W. DOUGHTY, citizens of the United States, residing at Binghamton, in the county of Broome and State of New York, have invented certain new and useful Improvements in Signal-Boxes, of which the following is a specification.

Our invention relates to a signal box for use in fire alarm systems of the non-interfering type, and has for its object to provide a signaling mechanism so arranged that it shall not be possible for interference to occur between the transmission of signals from different boxes. This object we attain by providing the signal box mechanism with a non-interference magnet which both mechanically controls the operation of the train and electrically controls the transmission of the signal. The magnet controls the operation of the box for a certain period of time, after which, the train, if it has been permitted to run, continues to rotate, regardless of the electrical conditions of the signaling circuit, for an additional period, at the termination of which the transmission of the signal is brought under the control of the magnet. The duration of the additional period above referred to is such that the box, once started, can not send a signal, until the electrical conditions of the signaling circuit are such as to permit such signals to be transmitted without interfering with signals from other boxes.

Referring to the drawings, Figure 1 is a diagrammatic view showing the box at rest capable of being tripped by the magnet as soon as it is energized; Fig. 2 shows the box after the train has been started showing the effect of a break in the external circuit during the "no control" period of the box; Fig. 3 shows the magnet in electrical control of the box during the first closure; Fig. 4 shows the effect of a break in the external circuit during the first closure; Fig. 5 is a detail to be later described; and Fig. 6 is a plan view of the signal wheel, pens and tracer. Figs. 7, 8, and 9 are diagrams to be explained later.

Referring to Fig. 1, the external or signaling circuit is connected to the box and to the binding posts A, B. A non-interference magnet 3 has an armature 4 to which is secured the armature lever 18 pivoted at 28.

A retracting spring 31 and stop-pin 32 con-

trol the backward movement of the armature lever. The lever 18 has an arm 19 for a purpose to be later described, and a pin 5 located on the back of the lever, and carries at its end a pivoted tracer 21 provided with a spring 26 mounted as shown in Fig. 6. Signaling pens 23, 24 serve to make and break the signaling circuit when operated by the teeth 22 and notches 25 of a wheel 44 rotated by the usual spring-driven clock train, the escapement of which is provided with a detent 16. This detent is controlled by an arm 15 mounted on the end of a lever 17 which is in turn mounted on a pivot 6, the arm 15 being itself mounted on a pivot 26 and having a laterally projecting arm 27 engaging the bottom of the lever 17 with which it is normally held in engagement by a spring 34. The lever 17 at its left hand end engages the pin 5 on the armature lever 18. The pivot 6 is carried by one arm 13 of a curved lever which is pivoted at 35, the other arm 14 of said lever having attached thereto a retracting spring 8 and carrying a contact 9. The arm 13 has at its upper side a ledge 2 having a notch 20. With this ledge 2 engages a pin 1 carried on the arm of a wheel 30 mounted on the shaft 33. The contact 9 cooperates with a contact 10 on a spring arm 101 secured to an insulating block 37. The spring arm 101 has a contact 12 arranged to cooperate with a contact 11 also carried by the block 37. The signal wheel 44 is at its rim provided with an overhanging flange 36 which is cut away at the notches in the manner shown in Fig. 1 and Fig. 6.

The signaling circuit is as follows:—The binding post A, wire E, magnet 3, wire F, pen 23, pen 24, wire I, binding post B.

A shunt circuit, which for convenience may be termed the "pen shunt" is as follows:—Binding post A, wire E, magnet 3, wire F, wire C, contacts 9, 10, arm 101, wire II, binding posts B. A second shunt, which may for convenience be termed the "box shunt" is provided in which the circuit is as follows:—Post A, wire G, contact 11, contact 12, part of spring arm 101, wire II, post B.

A modified form of signal wheel is shown in Fig. 5, the teeth 220 of the wheel 440 having overhanging flanges 221 to engage the tracer 21. In this arrangement the circuit remains closed between strokes. The first

notch 25 is shown as somewhat longer than the remaining notches of the round, but obviously it may be made of the same length.

The operation of the box is as follows:—

- 5 Assume the parts to be in the position shown in Fig. 1, and that circuit between binding posts A and B has been suitably energized. The magnet 3 is in circuit (binding post A, wire E, magnet 3, wires F, C, contact 9, contact 10, arm 101, wire H, binding post B), and the box shunt 11, 12, has been opened. The magnet 3 draws up its armature until tracer 21 strikes the top of flange 36, thus preventing arm 19 from engaging 101 and 10 breaking circuit between 9, 10. Pin 5 on lever 18 has however caused lever 17 to raise its right-hand end and arm 15 out of engagement with detent 16, so that the train can run. Pin 1 then moves across the face 15 of ledge 2, until it drops into notch 20, thus permitting arm 13 to rise, carrying the free end of 15 up to a point where it can no longer be brought into engagement with detent 16 even if armature 4 is released (see Fig. 2, which shows the armature released); the left-hand end of 14 dropping, but not far enough to open circuit at 9, 10. The armature is thus in mechanical control of the box as long as pin 1 is moving over the top 20 of ledge 2, but loses control, though still attracted, as soon as pin 1 drops into notch 20, because of the arm 15 having been put into an inoperative position by the raising of its pivot. During the time that pin 1 is 25 passing over ledge 2, tracer 21 is over flange 36, but the parts are so timed that before pin 1 drops off notch 20, pen 23 has reached the first notch in wheel 44 and closes 23, 24, thus providing a current path from post A 30 through magnet 3 to post B without passing through shunt contacts 9, 10. The tracer 21, immediately after the circuit has been closed at 23, 24, drops into the first notch 25, permitting the armature to be fully attracted 35 and its arm 19 to engage 101 and to raise contact 10 from contact 9. Thereupon the pin 1 drops off notch 20, the left-hand arm 14 lowering under the tension of the spring 8 and the right-hand arm 13 rising and raising pivot 6 of arm 17 to the position shown 40 in Fig. 3. The armature is now in control and if the circuit is interrupted while tracer 21 is opposite notch 25, the armature 4 will fall away from 3, withdrawing arm 19 and 45 permitting 11, 12 to close (Fig. 4) thereby shunting pens 23, 24 and also the magnet 3, after which the opening and closing of 23, 24 does not affect current between A and B, and current between A and B cannot affect 50 magnet 3 until wheel 30 has in its rotation brought pin 1 against the curved side of ledge 2, forcing it down into the position shown in Fig. 1, whereupon if the line is still open, detent 15 engages 16 and stops the 55 train, having previously, by upward move-

ment of arm 14, re-established connection at 9, 10, and broken the box shunt at 11, 12. When current is re-established armature 4 is attracted, tracer 21 drops on top of flange 36 preventing 19 from engaging 101 but permitting 17 to raise 15 away from 16, the operation being the same as before described upon starting the box. As the train rotates, flange 36 beyond the first notch 25 passes above tracer 21 just before engagement of the right-hand side of notch 25 raises pen 23 to break 23, 24 so that armature 4 cannot fall back. It will be noted that whenever pen 23 has fallen into a notch, such notch will be opposite tracer 21, thus permitting the armature to fall away from the magnet if not supported by the magnet, but just before pen 23 is lifted each time from pen 24, the notch in the flange 36 ends and said flange prevents tracer 21 and parts moving therewith from moving to a position where pin 19 would permit 11 and 12 to engage and thus shunt the box. During the sending of its own signal, therefore, the closed circuit keeps the armature attracted in the intervals of closure, and the flange and tracer mechanically hold the armature lever in the intervals of broken circuit.

The box when started is for a short period of time under the control of the magnet, so that if the external circuit is broken during this period, the box does not continue to run. This mechanical magnet-control is then disabled, but the electrical or circuit magnet-control is, after a short period in which there is no control, established so as to shunt the box in case of interference caused by other boxes breaking the circuit, and to provide for the sending of a signal when such interference is absent.

When the box is started and the pin 1 is passing over the top of the ridge 2, the running of the box will be under the control of the armature, the train starting when the armature is attracted and has thereby raised the detent 15, and stopping when the armature is retracted and thereby releases said detent. This period of armature control of the train, we shall refer to as the "mechanical magnet control" period. When the pin 1 reaches the lower part 20 of the ridge 2, lever 13 swings and carries detent 15 to an inoperative position so that while the tooth 20 is being passed over, the armature will be powerless to stop the train. This period when the tooth 20 is effective, we shall refer to as the "no control" period. During the "mechanical magnet control" period and that "no control" period, contacts 9 and 10 remain in engagement to keep the "pen shunt" closed. However, when the pin 1 reaches the end of the ridge on lever 13, this lever will swing farther and will release contact 10 and thereby open the "pen shunt," but at substantially the same time the tracer 130

21 on armature lever 18 comes opposite the first notch and the armature can become fully attracted to carry its end 19 upwardly to prevent engagement of contact 12 with 5 contact 11 and thereby keep the box shunt open, provided the magnet is energized. The "electrical magnet control" period now starts, then continues until the signal contacts break for the first time. During this 10 "electrical magnet control" period, the armature is free to retract should the line be open at any external point so that upon such opening, the contacts 12 and 11 may come into engagement to close the box shunt, 15 and to thereby prevent further attraction of the armature until this box shunt is again opened just before the beginning of the next round by the lever 18.

The period during which the box runs 20 subsequent to the termination of the period of mechanical magnet-control and previous to the start of the period of electrical magnet-control must bear such relation to the sequence of breaks and closures in the signals 25 from other boxes that if any closure in such signals has energized the magnet 3 and thereby released this box the electrical magnet-control period will occur during some open circuit period following the closed circuit period which first energized magnet 3. The period which elapses from the termination 30 of the mechanical control till the beginning of the electrical control may be shorter than any open circuit period in a signal, or such period may be longer than any open-circuit period in a signal provided that such period ends after the box 35 has run for a time greater than one or more breaks and closures, and that such no-control period ends at a time such that the circuit is open during all or some part of the period of electrical control. Thus if a signal from box 54, consisting of five closed and open periods, the fifth open period being longer than the preceding open periods, and then four closed and open periods, the 40 fourth open period being longer than the period between the five closures and the four closures, was in course of transmission over 45 a circuit, at a time when the box mechanism as shown in Fig. 1 was placed in control of such circuit, the first closure which occurred in such signal after the box was placed in control would energize the magnet 3, thereby attracting the armature 4 and withdrawing 15 from 16, and allowing the rotation of wheel 44. If now, the magnet 3 was so energized by the first closure in the 50 group of five, and the rotation of wheel 44 is so timed that tracer 21 is opposite first notch 25 during any part of any of the breaks in the signal, it is evident that the magnet 3 will permit the armature 4 to assume such position that contacts 11, 12, will 55 be permitted to close and shunt the magnet

3 and pens 23, 24. It is also evident that had the mechanical control during the rotation of wheel 44 continued until the electrical control was established the movement of wheel 44 would have been arrested during 60 any break or breaks occurring in the transmission of signal 54 subsequent to the closure which first energized magnet 3, and wheel 44 would be again permitted to rotate during each succeeding closure; and thus 65 the rotation of wheel 44 might be arrested just prior to the period of electrical control, and in that event, the next succeeding closure from signal 54 would start practically at the same time as the commencement 70 of the period of electrical control, thereby permitting wheel 44 to rotate in synchronism with the signal from box 54 and by holding the circuit open while the portion of said wheel 44 between the second 75 and third notches of said wheel was passing under the pen 23 and the tracer 21 was locked beneath flange 36, to interrupt the signal from box 54. But, by permitting the box to run regardless of any breaks 80 which may occur in the circuit from the time the pin 1 disengages the ledge 2, until the electrical control is established and the first notch 25 is opposite the tracer 21, such notch 25 is presented to tracer 21 after the 85 elapse of such a period of time from the closure which first energized the magnet 3, that the transmission of signal 54 will open the circuit while said notch 25 is in the path of tracer 21 regardless of which closure in such signal 54 caused the magnet 3 to 90 be initially energized. It is thus apparent that the length of the period during which the pin 1 is passing over the notch 20, may 95 be comparatively short or comparatively long, as long as the relation of such period to the period between a closed circuit interval and a succeeding open circuit interval be maintained as above specified.

The mechanisms for starting and stopping the box have not been shown, as mechanism for this purpose is well known in the art.

Fig. 7 shows diagrammatically the closures and openings of the circuit during the sending of the signal 54. Figs. 8 and 9 show the durations of the mechanical magnet control M, and the electrical control E, relatively to the closures and openings shown in Fig. 7. The interval between M and E may be either short or long; the signal wheels of each of the boxes of the system being so cut with relation to this interval between the controls that the electrical control is always established at an open-circuit point in the signal.

The tracer 21 is spring-controlled in the manner shown so that in case the circuit breaks at a time when the flange 36 of a tooth 22 would be brought against the tracer 21 by rotation of the wheel 44, the tracer can 130

yield without stopping the train. A suitable stop on the arm 18 prevents the tracer 21 from being drawn farther back than the position shown in Fig. 6.

5. We claim:

5. 1. In a signaling box, the combination of a non-interference electromagnet and armature, a signaling train, means for causing the armature to control the running of the train for a period after starting of the box, means for allowing the signaling train to run independent of the armature for a period after such armature control period, a disabling circuit closed during said first and second periods to prevent signaling operation, and means for causing said armature to control said disabling circuit for a period after said period of independent running of the train.
10. 2. In a signal box, a magnet, its armature, an armature lever, a signaling train, a locking lever for said train, a second lever to which said locking lever is pivoted, means on said armature lever for operatively engaging said locking lever, and means connected to the train for operating said second lever independently of said locking lever.
15. 3. In a signal box, a magnet and an armature structure therefor, a signaling train, a locking lever for said train, a second lever to which said locking lever is pivoted, means on said armature structure for operatively engaging said locking lever, and means driven by the train for operating said second lever to successively adjust the locking lever
20. 35. to bring the running of the train under its control and to disengage it from such control.
4. In a signal box, a magnet, its armature, an armature lever, a signaling train, a locking lever for said train, a second lever to which said locking lever is pivoted, means on said armature lever for operatively engaging said locking lever, and means connected to the train for operating said second lever, said means comprising a pin on a
45. 45. wheel of said train and a ledge on said second lever.
5. In a signal box, a magnet, its armature, an armature lever, a signaling train, a locking lever for said train, a second lever to which said locking lever is pivoted, means on said armature lever for operatively engaging said locking lever, and means connected to the train for operating said second lever, said means comprising a pin on a
55. 55. wheel of said train and a ledge having a notch on said second lever.
6. In a non-interference signal box, the combination with a magnet and its armature and a signaling train of a switch controlling a shunt around the signaling device, a second switch controlling a shunt around the magnet and signaling device, and means operable by the magnet for controlling both switches and separate means operable by the train for directly controlling both switches.

7. In a non-interference signal box, the combination with a magnet and its armature and a signaling train of a switch controlling a shunt around the signaling device, a second switch controlling a shunt around the magnet and signaling device, and means controlled by the train for successively directly operating said switches.

8. In a non-interference signal box, the combination with a magnet and its armature and a signaling train of a switch controlling a shunt around the signaling device, a second switch controlling a shunt around the magnet and signaling device, and means controlled by the train for directly operating both switches.

9. In a non-interference signal box, the combination with a magnet and its armature, a signaling train, and a signaling device of a switch controlling a shunt around the signaling device, a second switch controlling a shunt around the magnet and signaling device, and means connected to the armature for operating both switches.

10. In a non-interference signal box, the combination with a magnet and its armature, a signaling train, and a signaling device of a switch controlling a shunt around the signaling device, a second switch controlling a shunt around the magnet and signaling device, an arm carrying one contact of each switch, and separate means controlled by the armature and the train for operating said arm.

11. In a non-interference signal box, the combination with a magnet and its armature, a signaling train, and a signaling device of a switch controlling a shunt around the signaling device, a second switch controlling a shunt around the magnet and signaling device, a spring arm carrying one contact of each switch, and separate means controlled by the armature and the train for operating said arm.

12. In a signal box, a magnet, an armature, an armature lever, a signal train, locking mechanism for the train comprising a locking lever for said train, having one arm adapted to engage such train and the other arm engaging the armature lever, and a movable support for such locking lever; means for holding said locking mechanism out of the locking position, and means operated by the train for causing said locking mechanism to move successively into and out of the locking position.

13. In a signal box, a magnet, an armature, an armature lever, a signal train, signal controlling mechanism, a shunt circuit therefor, a shunt-switch, locking mechanism for the train comprising a locking lever for said train, having one arm adapted to engage such train and the other arm engaging the armature lever, and a movable support for such locking lever; means for holding

5 said locking mechanism out of the locking position, and means operated by the train for causing said locking mechanism to move successively into and out of the locking position, said support having means for operating the shunt-switch.

14. In a signal box, a non-interference magnet, a circuit-breaking device in series with said magnet and a train for operating the same, a shunt around both the magnet and circuit-breaking device, a second shunt around the circuit-breaking device only, switches in said shunt circuits, and a common means for first establishing the first 15 shunt and then breaking the second shunt.

15. In a signal box, a non-interference magnet, a circuit-breaking device in series with said magnet and a train for operating the same, a shunt around the magnet and 20 circuit-breaking device, a second shunt around the circuit-breaking device only, switches in said shunt circuits, and means, operated by the train, for establishing the first shunt before the second shunt is broken.

25. 16. In a signal box, a non-interference magnet, a circuit-breaking device in series with said magnet and a train for operating the same, a shunt around both the magnet and circuit-breaking device, a second shunt 30 around the circuit-breaking device only, switches in said shunt circuits, means operated by the train for establishing the first shunt before the second shunt is broken and means controlled by the magnet for operating 35 the second shunt switch.

17. A signal box comprising a signaling train including normally inoperative signal transmitting means, a non-interference magnet, a magnet control for the said train, 40 train-controlled means for disabling the magnetic control, means for holding the said magnet control and the said signal transmitting means disabled, and switches controlled by the said magnet and the said train controlled means for controlling the signal 45 transmission.

18. A signal box comprising a signaling train including normally inoperative signal transmitting means, a non-interference magnet, a mechanical magnet control for the starting period of the said train, train-controlled means for disabling the said magnet control, means for holding the said magnet control and the said signal transmitting 50 means disabled, and means controlled by the said magnet and the said train-controlled means during open circuit periods for controlling the operativeness of the said signal transmitting means.

60. 19. A signal box comprising a signaling train, including normally inoperative signal transmitting means, a non-interference magnet, a mechanical magnet control for the starting periods of the said train, train-controlled means for disabling the said magnet

control, means for holding the said magnet control and the said signal transmitting means disabled, means controlled by the said magnet and the said train-controlled means during open circuit periods for controlling 70 the operativeness of the said signal transmitting means, and means for holding the said signal transmitting means in its operative position.

20. A signal box comprising a signaling 75 train, including normally inoperative signal transmitting means, a non-interference magnet, a mechanical magnet control for the starting periods of the said train, train-controlled means for disabling the said magnet control, means for holding the said magnet control and the said signal transmitting means disabled, means controlled by the said magnet and the said train-controlled means during open circuit periods for controlling 80 the operativeness of the said signal transmitting means, means for holding the said signal transmitting means in its operative position, and means for controlling the reestablishment of the said mechanical control.

21. A signal box comprising a signaling 85 train, including normally inoperative signal transmitting means, a non-interference magnet, a mechanical magnet control for the starting periods of the said train, train-controlled means for disabling the said magnet control, means for holding the said magnet control and the said signal transmitting means disabled, means controlled by the said magnet and the said train-controlled means during open circuit periods for controlling 90 the operativeness of the said signal transmitting means, means for holding the said signal transmitting means in its operative position, and means for controlling the reestablishment of the said mechanical control.

22. A signal box comprising a signaling 95 train including signal transmitting means, a non-interference magnet, a mechanical magnet control for the said train, train-controlled means for disabling the said mechanical magnet control but preventing control of the said signal transmitting means, 100 means adapted to be controlled by the said magnet and the said train-controlled means for holding the said mechanical magnet control disabled and for controlling the said signal transmitting means, and means for throwing the said controlling means successively into action.

23. In a non-interference signal box, the combination with a normally inoperative signaling device, a magnet and its armature 110 and a signaling train, of a switch controlling a shunt around the signaling device, means controlled by the train for moving the said signaling device into operative position, separate means controlled by the train for 120

125

controlling the said shunt-controlling switch subsequent to the operation of the said signaling device controlling means, a second switch controlling a shunt around the magnet and signaling device and means operable by the said magnet and by the said separate train-controlled means for controlling the said second switch.

24. In a non-interference signal box, the combination with a normally inoperative signaling device, a magnet and its armature and a signaling train, of a switch controlling a shunt around the signaling device, means controlled by the train for moving the signaling device into operative position, separate means controlled by the train for controlling the said shunt controlling switch, a second switch controlling a shunt around the magnet and signaling device, and means operable by the said magnet and by the said separate train-controlled means for controlling the said second switch, and means for successively operating said switches.

25. In a signal box, a non-interference magnet, a normally inoperative circuit-breaking device in series with said magnet and a train for operating the same, a shunt around both the magnet and circuit-breaking device, a second shunt around the circuit-breaking device only, a train-controlled switch adapted to control the said shunt around the magnet and circuit-breaking device and to control both of the shunts simultaneously, and a magnet-controlled switch controlling the said first shunt.

26. In a signal box, a non-interference magnet, a normally inoperative circuit-breaking device in series with said magnet and a train for operating the same, a shunt around both the magnet and circuit-breaking device adapted to be opened after the circuit-breaking device is placed in operative position, a second shunt around the circuit-breaking device only, a train-controlled switch adapted to control the said shunt around the magnet and circuit-breaking device and to control both of the shunts simultaneously, and a magnet-controlled switch controlling the said first shunt.

27. In a signal box, a non-interference magnet, a normally inoperative circuit-breaking device in series with said magnet and a train for operating the same, a shunt around both the magnet and circuit-breaking device, a second shunt around the circuit-breaking device only, a train-controlled switch adapted to control the said shunt around the magnet and circuit-breaking device and to control both of the shunts simultaneously, a magnet-controlled switch controlling the said first shunt, and means for establishing the first shunt before the second shunt is broken.

28. In a non-interference signal box, the combination with a normally inoperative

signaling device, a magnet and its armature, and a signaling train, of a switch controlling a shunt around the signaling device, a second switch controlling a shunt around the magnet and signaling device, a mechanical magnet-control for the said train, train-controlled means for disabling the said magnet-control but preventing operation of the said switches, and means controlled by the said magnet and the said train-controlled means for controlling the switches, after the magnet-control has been disabled.

29. In a non-interference signal box, the combination with a normally inoperative signaling device, a magnet and its armature, and a signaling train, of a switch controlling a shunt around the signaling device, a second switch controlling a shunt around the magnet and signaling device, a mechanical magnet-control for the said train, train-controlled means for disabling the said magnet-control but preventing operation of the said switches, means controlled by the said magnet and the said train-controlled means for controlling the switches, after the magnet-control has been disabled, and means for re-establishing the said magnet-control and restoring the said switches.

30. In a non-interference signal box, the combination with a normally inoperative signaling device, a magnet and its armature, and a signaling train, of a switch controlling a shunt around the signaling device, a second switch controlling a shunt around the magnet and signaling device, a mechanical magnet-control for the said train, train-controlled means for disabling the said magnet-control but preventing operation of the said switches, means controlled by the said magnet and the said train-controlled means during open circuit periods for controlling the switches, after the magnet-control has been disabled, and means for re-establishing the said magnet-control and restoring the said switches.

31. In a non-interference signal box, the combination with a normally inoperative signaling device, a magnet and its armature, and a signaling train, of a switch controlling a shunt around the signaling device, a second switch controlling a shunt around the magnet and signaling device, a mechanical magnet-control for the said train, train-controlled means for disabling the said magnet-control but preventing operation of the said switches, means controlled by the said magnet and the said train-controlled means during open circuit periods for controlling the switches after the magnet-control has been disabled, and means for locking the switch-controlling means.

32. In a non-interference signal box, the combination with a normally inoperative signaling device, a magnet and its armature, and a signaling train, of a switch controlling

a shunt around the signaling device, a second switch controlling a shunt around the magnet and signaling device, a mechanical magnet-control for the said train, train-controlled means for disabling the said magnet-control but preventing operation of the said switches, means controlled by the said magnet and the said train-controlled means during open circuit periods for controlling the switches after the magnet-control has been disabled, means for locking the switch-con-

trolling means, and means for unlocking the switch-controlling means and for restoring the said switches and the said magnet-control.
